UNITED STATES PATENT OFFICE.

EMANUEL EINSTEIN, OF NEW YORK, N. Y.

DESIGN FOR NAP-SURFACE OF CLOTH.

SPECIFICATION forming part of Design No. 12,297, dated June 7, 1881.

Application filed March 14, 1881. Term of patent 3½ years.

To all whom it may concern:

Be it known that I, EMANUEL EINSTEIN, of New York, in the county and State of New York, have designed a new and original Design for the Nap-Surface of Cloths, of which the following, in connection with the accompanying drawing, is a full, clear, and exact description.

This design is related to that class of designs which are intended to be cut into the nap or pile of smooth-finished cloths in the act of shearing the same, such as is shown in the patent of Felix Samson, dated February 15, 1881, No. 12,176; and while these designs might be produced on the cloth in other ways than cutting, yet no other mode is contemplated or is so desirable, as a very agreeable and novel effect is obtained by the contrast of the sharply-cut grooves or figures with the smooth, level nap of the cloth.

My present design is one of several of the aforesaid character filed on the same date as this; and it consists in a special form and arrangement of lines or grooves, producing a new effect, as hereinafter set forth.

The figure in the annexed drawing gives a face view of a piece of cloth finished according to my design.

In this figure the field of the design consists of the smooth or finished nap of the cloth, forming a uniform, level surface, while the lines represent grooves cut into this nap.

The chief feature of my present design, as shown in the annexed drawing, consists in the combination of bands of transversely-diagonal lines *a a*, intervening with bands *b b*, containing a bold to-and-fro zigzag line, *c*, extending longitudinally and displaying triangles of plain or smooth nap between its bands, which contrast agreeably with the closely-grooved 40 diagonal bands *a a*. I usually prefer to run a stripe of one or more straight lines, *e e*, as shown, between the diagonal and zigzag bands, to give a more full, finished, and ornate effect; but these are not essential. 45

What I claim is—

1. The design for the nap-surface of cloths, consisting of bands of diagonal lines alternating with bands traversed by a to-and-fro zigzag line extending lengthwise thereof, substantially as herein shown and described. 50

2. The design for the nap-surface of cloths, consisting in the combination of bands of diagonal lines, straight lines, and zigzag lines, alternating with each other in distinct parallel rows, substantially as herein shown and described. 55

EMANUEL EINSTEIN.
